(57) **CLAIM**

The ornamental design for an exercise aid, as shown and described.

DESCRIPTION

FIG. 1 is a front elevational view of an exercise aid in accordance with one embodiment of the invention, the rear elevational view being identical;

FIG. 2 is a left elevational view of the exercise aid of FIG. 1, the right elevational view being a mirror image of FIG. 2; FIG. 3 is a top elevational view of the exercise aid of FIG. 1,

FIG. 4 is a bottom elevational view of the exercise aid of FIG. 1;

FIG. 5 is a front perspective view of the exercise aid of FIG. 1; and,

FIG. 6 is a front elevational view of the exercise aid of FIG. 1 wherein the handles are in a second relative position.
